(57) **CLAIM**

I claim the ornamental design for a vehicle steering wheel, as shown.

DESCRIPTION

FIG. 1 is a right, front perspective view of a vehicle steering wheel showing my new design;

FIG. 2 is a left, front perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.
